UNITED STATES PATENT OFFICE

DOROTHY P. MURPHY, OF BABYLON, NEW YORK

DESIGN FOR A COMPOSITE FABRIC

Application filed April 11, 1933. Serial No. 47,754. Term of patent 3½ years.

To all whom it may concern:

Be it known that I, DOROTHY P. MURPHY, a citizen of the United States, residing at Babylon, in the county of Suffolk and State of New York, have invented a new, original, and ornamental Design for Composite Fabric, of which the following is a specification, reference being had to the accompanying drawing, forming part thereof.

In the drawing—

Fig. 1 is a plan view of a composite fabric showing my new design;

Fig. 2 is an end view of Fig. 1 showing the raised character of the composite fabric consisting of a base of woven or textile material having superposed thereon a plurality of individual textile flowers in overlapping relation.

I claim:

The ornamental design for a composite fabric substantially as shown and described.

In testimony whereof I have hereunto set my hand on this 6th day of April, 1933.

DOROTHY P. MURPHY.
